METHOD OF COATING CONTAINERS

Henry T. Scott, Toledo, Ohio, assignor to The American Paper Bottle Company, Toledo, Ohio, a corporation of Ohio

Application October 16, 1934, Serial No. 748,563

4 Claims. (Cl. 91—70)

This invention relates to methods of coating containers and particularly to methods of applying coatings to paper containers primarily intended for the packaging and dispensing of liquids.

In Patent No. 2,047,891, issued July 14, 1936, is disclosed a paper container which, while well adapted to serve as an envelope for commodities of various kinds, is particularly suitable for the packaging of liquids. It is fabricated of relatively stiff paper and is in the form of a tube of rectangular cross section with its upper and lower ends sealed. Where liquids are to be charged into the container prior to sealing it is essential that the container in its entirety be given a coating of some substance which will render the same liquid proof so that no leakage may subsequently occur. The coating material which I may employ may vary considerably, or in accordance with the characteristics of the materials which are to be packaged. Where food products are to be packaged, particularly milk or milk products, it is highly desirable that the liquid proofing coating substance should be of such character as to remain neutral in the presence of the liquid contents of the package while at the same time performing its function of preventing contact with the paper of the liquid contents of the container, thereby preventing softening of the walls of the container and also occupying any minute openings in the paper itself or between the joints of the container and thereby preventing direct leakage.

The method which comprises the subject matter of the present invention may be carried out in a mechanism designed especially to receive from a container fabricating machine a container of the type shown in my patent above referred to, to move this container through a bath of molten paraffin to drain the excess paraffin therefrom after issuing from the bath, and finally to eject the container from the paraffining apparatus and to position the same so as to be readily engageable by a conveyor mechanism for transporting to other apparatus for charging, closing and sealing. The container as it comes to the paraffining unit has its bottom closed and top open. It is introduced into the bath of paraffin bottom end foremost so that the molten paraffin has access to the interior of the container only after the open end of the container has been moved below the surface of the paraffin bath. As the container fills with paraffin the air which is contained therein is displaced by the paraffin, the incoming stream of paraffin running immediately to the bottom of the

container and the level of the liquid rising rapidly from the bottom toward the open top thereof thus insuring that all contained air is expelled. After the container has been completely submerged it is carried through the paraffin bath in such manner that all of its surfaces are thoroughly exposed to the paraffin, the container not being positively held by any of the carrying mechanism but being so transported in a carrier that it may have limited movements relatively to the carrier in all directions and may freely respond, to a limited extent, to the surging movements of the paraffin bath brought about by the operation of the mechanism. Each individual paper fibre of the container, both upon the outer and inner surfaces thereof is so exposed to the coating substance that the container as it issues from the bath is completely and thoroughly coated with the impregnating substance.

While the improved method is particularly useful when employed in the treatment of paper containers of square cross-section, it will be obvious to one skilled in the art that it may likewise be used in the coating of paper containers which vary widely in shape and size. Likewise it will be appreciated that the method may be practiced by the aid of mechanisms which differ substantially in design and specific mode of operation. In the accompanying drawings one form of such mechanism is illustrated, by means of which the method may be conveniently practiced, and this mechanism will be described in detail. It is, however, as will be understood, but one of a number of mechanisms which may be employed for this purpose.

In the drawings:

Figure 1 is a view of the coating apparatus taken from the side, many of the parts being shown in section and others having been removed for the purpose of more fully disclosing interior details;

Figure 2 is a view of the apparatus as it would be seen from the right (Figure 1) certain of the operating parts being shown in elevation and certain parts being broken away to show the underlying elements;

Figure 3 is a view of the apparatus as from the left (Figure 1) certain of the parts being shown in section and others partially broken away;

Figure 4 is a side elevation, partly broken away, of a container receiving unit which forms part of the apparatus;

Figure 5 is a section on line 5—5 of Figure 1;

Figure 6 is a section on line 6—6 of Figure 1;

Figure 7 is a section on line 7—7 of Figure 3;

Figure 8 is a section on line 8-8 of Figure 6; and

Figure 9 is a perspective view of one of the container carriers.

5 The apparatus is designed for the rapid handling of a continuous series of paper containers, receiving successive containers presented to it, passing these containers through the paraffin bath and effecting the discharge thereof. It is 10 primarily intended to form portion of a rapidly operating automatic machine in which blanks are rapidly detached from a pack, erected into tubular form, closed at one end, coated, charged, closed and sealed. It may of course be made 15 to have any desired capacity and rate of operation.

The casing or housing in which the bath of paraffin is enclosed and which also houses the operating parts of the coating mechanism is 20 indicated at 10, the lower portion of this housing being especially designed for the retention of a substantial body of molten paraffin while the upper portion may be of lighter construction. A removable bottom plate is indicated at 11 and this plate may be taken off whenever it is desired to clean the apparatus. The normal paraffin level is indicated by the letter L and it will be understood that additional quantities of paraffin will be introduced from time to time to 30 replace that which passes out in the shape of surface coatings upon the containers which pass through the apparatus. A conveyor chain is indicated at 12 this chain being endless and is supported upon three sprockets 13, 14 and 15 35 one of which as for instance the sprocket 15, may be intermittently driven by any suitable mechanism. A guide 16 serves to support the conveyor chain at one point where it changes the direction of its travel. Mounted upon certain of the individual links of this chain are container carrying elements 18 and there are a relatively large number of these elements, only a few being illustrated. Carriers 18 are closely spaced and the chain is so driven that each carrier is 40 advanced from its container receiving position, indicated at B in Figure 1 to its container discharging position indicated at D by a series of step by step movements. One of the carriers is shown in perspective in Figure 9 and it is shown in this figure at the angle which it makes with the horizontal when the conveyor chain link to which it is secured is moving in a vertical path. It comprises essentially a five sided box like member with somewhat greater interior dimensions 45 than the exterior dimensions of the container, indicated at C in chain lines, which it is to house and to transport through the bath. Any suitable means may be utilized for securing the rear wall of the container to a chain link and the rear wall of the carrier, which faces the open side, is also provided with a series of apertures 19 through 50 which paraffin may enter the carrier and which also permit the introduction of ejecting rods for effecting the discharge of the container, in a manner to be hereinafter more fully described.

The other two larger walls of the carrier, indicated at 20 and 21, are imperforate and the wall 20 is also curved or made concave, as shown, while the wall 21 is preferably flat. The end 55 walls of the carrier have apertures 22 formed therein to permit the free entry and escape of liquid paraffin. That end of the carrier which is lowermost at the time that the container to be coated is introduced therein, is provided with an 60 inner central transversely extending rib 23 which

acts as a limiting stop for the movement of the container toward that end of the carrier during the paraffining operation thus preventing the end flaps C' of the container from striking the end of the carrier and safeguarding these ends against injury from such contact. 5

The carriers shown to the right (Figure 1) descend in the operation of the device and are empty. As each carrier reaches the position of the carrier indicated at B the motion of the conveyor chain is temporarily halted and a container is introduced into the same to occupy the position shown in Figure 9. The means for introducing the container will now be described. 10

A container receiving chute is indicated generally at S this chute being vertically disposed to receive containers successively dropped into the same by mechanism which is not illustrated. The chute includes oppositely facing stationary guide plates 30 and oppositely facing swinging 20 guide plates 31. Plates 31 are secured at their lower ends to the upstanding side members 32 of a U-shaped frame generally indicated at 33. Frame 33 has integral therewith a laterally extending cylindrical bearing member 34 which is rotatably 25 supported upon a cylindrical stud 35 mounted in the end of a supporting frame member 36. The frame therefore, together with the plates 31, may swing or oscillate about the axis of stud 35 from the position in which it is shown in Figure 4 to 30 the position in which it is shown in Figure 5. Assuming that a container is dropped into the chute with open end lowermost, as indicated at C' in Figure 4, the swinging motion of the movable portion of the chute, including the plates 31 35 and frame 33 effects the movement of the container to the position indicated at C² in Figure 5, the closed bottom of the container then being lowermost and the container occupying a position inclined to the horizontal. 40

To effect this swinging movement the frame is connected to a drive shaft 37, the teeth of a segment 38 integral with sleeve 34 meshing with the teeth of a second segment 39 pivotally mounted upon a stud 40 and segment 39 being integral 45 with an arm 41 which is connected by means of a link 42 with the upper end of a lever 43, lever 43 being pivoted to the frame at 44 and carrying a roller 45 which lies within a camway formed within a cam 46 mounted upon shaft 37. Rotation of cam 46 therefore results in oscillation of the frame from its upper vertically disposed position to its lower inclined position in timed relation to the other operating parts of the mechanism. 50

The movements of the container positioning frame just described are coordinated with the movements of the conveyor chain and, when a container has been removed to the position indicated at C² in Figure 5, it is in register with the carrier B within the housing 10, and also in register with an aperture formed in the wall of the housing. It is therefore in a position to be moved laterally inwardly of the housing and into the mouth of carrier B which is positioned to receive it. The means for effecting this inward movement includes the pusher 40 slidably mounted upon the frame for horizontal movement, the pusher 40 having the same inclination to the horizontal as have the apertures formed in the housing and also the carrier B. For effecting sliding 70 movement of the pusher it is connected to an intermittently oscillating lever 41 by means of link 42, lever 43, and link 44, the lever 43 being mounted upon a fixed pivot 45. 65

The means for oscillating lever 41 is not illus- 75

trated but it will be understood that any suitable means may be employed to operatively connect this lever to shaft 37 and to produce oscillations of this lever at properly timed intervals. Immediately after oscillating to thrust a container C laterally into the carrier B the pusher is retracted and the frame 33 and blades 31 are swung to vertical position to receive a following container. The conveyor chain is actuated and as the carrier just changed moves downwardly an unloaded carrier coming into register with the container charging opening formed in the housing wall and ready to receive the next following container. The carrier B within which a container has just been placed will be moved downwardly into the paraffin bath, thence horizontally toward the left (Figure 1), and finally upwardly until it occupies the position D.

As may be seen from an inspection of Figure 1 one of the bottom edges of the container C first reaches the level of the upper surface of the paraffin and the bottom of the container is lowermost during the time that the container is actually undergoing the process of immersion so that any air originally within the same is displaced by molten paraffin, flowing upwardly and making its escape from the paraffin bath. Eventually the carrier turns around the axis of sprocket 13 and assumes a horizontal position. In this movement the open side of the carrier is turned downwardly and, when the carrier has reached a completely horizontal position as indicated at B², is facing directly downwardly, the container either resting against that wall of the carrier which has heretofore been designated the rear wall, and which is connected to the associated chain link, or resting against the curved guide plate 47 and being moved along this plate by the action of the carrier.

When the carrier reaches the position indicated at B³ the container which it carries is about to emerge from the paraffin bath with its closed bottom uppermost so that the paraffin will drain rapidly from its interior. Eventually, and after a further series of step by step movements of the conveyor, the carrier with its coated container reaches the position D (Figure 1), and may then be ejected from the housing. For the purpose of bringing about this ejection an ejecting mechanism is provided which includes a plurality of parallel ejecting fingers 50 supported at their rear ends upon a vertically disposed plate 51 the lower end of which is slidably supported upon guide rods, one of which is indicated at 52.

Each finger 50 is in alignment with an aperture formed in a perforated guide plate 53 and also in alignment with the perforations 19 formed in the rear wall of carrier D when that carrier has reached the discharge position shown in Figure 1. Slide 51 is operatively connected by means of a link 54, lever 55 and link 56 with the upper end of oscillating lever 41 previously referred to and will be reciprocated forwardly and rearwardly when lever 41 is actuated. When reciprocated forwardly or to the left (Figure 1) the fingers 50 after passing through the perforations in guide plate 53 and through the registering perforations 19 in the rear wall of the carrier D will contact with the inner wall of the container C housed within the carrier and will thrust this container outwardly through an aperture formed in the housing to permit its passage and into a rocking frame 60 which at that instant is positioned to receive it. The rocking frame 60 includes a member 61 one end of which is pro-

vided with two hubs 62 and 63 rotatably mounted upon a supporting stud 64 so that this frame member may have swinging movement about the axis of stud 54.

Frame member 65 has a hub 66 which is keyed to stud 64 so as to be rotatable therewith, hub 66 lying intermediate hubs 62 and 63 of frame member 61. A spring pressed detent 67 carried by hub 66 normally has its outer end projecting within shallow recess 68 formed in hub 62 and hence hubs 62, 63 and 66 will normally rotate in unison about the axis of stud 64. Secured to the ends of frame members 61 and 65 respectively are the guiding and retaining blades 70 which are container holding members, having inturned outer ends 70' to insure retention of the container as the entire frame as an entirety swings downwardly.

As will be seen from Figure 6 a container just discharged from the housing will occupy the position C³ its open end being lowermost. It will be understood of course that as the container is ejected from the housing, the receiving frame just described is in register with the aperture formed in the housing. A rotatory movement is then transmitted to the stud 64 by mechanism which is illustrated in Figure 3 and is seen to include a segment 71 fixed on stud 64, the teeth of this segment meshing with the teeth of a segment 72 pivotally supported at 73 upon a frame member. Oscillation of segment 72 is effected by means of link 74 the lower end of which is connected to a lever 75 carrying a roller 76 which is in engagement with a cam 77 mounted on shaft 37.

Two cushioning springs 78 adapted to be engaged by one or the other of abutment 79, respectively, on link 74 dampen shocks incidental to the operation of the mechanism just described, the adjacent ends of these springs bearing against a common central spring abutment 80.

By reason of the fact that the hubs of frame members 61 are not positively connected to the oscillating driving studs 64 but are only releasably connected to this stud through the intermediary of the detent 67, it is not possible for breakage to occur should for instance a container come to rest after having been only partially introduced into the rocking frame and between the container supporting blades 70, portion of the container for instance still overlying the edge of the discharge aperture formed in the housing. Should the rocking frame, including members 61 and 65, start downwardly with a container in such position as this the opposition to the movement of frame member 61 and its associated blades 70 offered by the container will be sufficiently great to cause the detent 67 to be cammed into its receiving recess and out of recess 68, thus permitting rotation of hub 66 and frame member 65 relatively to hubs 62 and 63 and frame member 61. The operator perceiving the separation of the two elements of the transfer frame will stop the machine and remove the jammed container whereupon the frame member 61 may be again swung to its normal relative position with respect to frame member 65, the detent 67 again entering recess 68 and releasably locking the hubs together.

After a container discharged from the housing in a normal manner has been lowered to the position in which it has been indicated at C⁴ in Figure 6 it is to be removed from between the arms 70 and moved forwardly into a position to

be engaged by a conveyor. This movement from between arms 70 is effected by means of an extractor 82 which comprises an angular member the lower horizontal end of which is secured to a 5 reciprocal member 83 and the vertical portion of which lies parallel to the housing wall and, in its rearmost position, lies within a recess formed within the housing wall. Member 83 is guided in its reciprocating movements by means of parallel guides one of which is indicated at 84 and to the under side of this member is secured a rack 85 the teeth of which mesh with the teeth of a gear 86 fixed upon a shaft 87. Shaft 87 is rotatably supported in a bearing 88 and carries 10 at its outer end a pinion 89 the teeth of this pinion meshing with the teeth of a rack 90 slidably supported for longitudinal movements and carrying a roller 91 which lies within a camway formed in the revoluble cam 92 also fixed on shaft 31. 15 Revolution of cam 92 therefore results in reciprocating movement of slide 83 and hence causes the extractor finger to move outwardly between blades 70 at the proper time and to remove a container which may be standing between these blades.

As mentioned previously the container will then pass on to a suitable conveyor which is not illustrated. The transfer frame including frame members 61 and 65 is enclosed save for a container outlet port formed in the forward wall thereof and within this housing is located a heating unit, in this case including the conduit 93 for a heating medium such as steam as it is desired to maintain the paraffin upon the container walls in liquid condition at this point. Also mounted upon this housing is a steam chamber 94 for maintaining the interior temperature of the housing at the proper point.

The various mechanisms described are of course actuated in a desired timed relationship, a container to be coated being inserted into an empty carrier at the same time that a coated container is being ejected from the housing.

I find it to be preferable, in fabricating containers to be subsequently coated with a coating substance such as paraffin, to utilize a paper which is porous in order that the paraffin may penetrate into the interstices thereof. Hard papers can be rendered liquid proof only with great difficulty and the coating is often non-uniform over the surface of the article made therefrom. To insure that the paper used has the necessary mechanical strength and stiffness, and at the same time the necessary porosity, a somewhat thicker sheet is used than would be necessary were the paper harder. A paper of the solid bleached sulphite type having a weight of approximately .028 pound per .001 inch thickness per square yard has been found to be satisfactory. Kraft paper may also be used and also combinations of kraft and sulphite papers. In any event paper of the desired porosity will have a considerable nap comprising projecting fibers or filaments and it is desired that all of these projecting fibers be thoroughly coated during the coating operation.

As the container enters the paraffin bath, the moisture and air between the fibers of the paper is expelled by the action of the paraffin. It is essential that the spaces left vacant by the exclusion of moisture and air be filled with coating material so that a continuous leakproof coating is provided. As the container enters the paraffin bath, its lowermost side wall is first presented to the liquid paraffin in such a posi-

tion that the air and moisture in the pores of the paper may pass freely upward. Following this the then uppermost side wall will be so presented and immersed. The bottom also is disposed at such angle that the discharge of moisture and air therefrom is facilitated. As the container progresses further into the paraffin bath, to the horizontal position, the sides of the container which were previously vertical become horizontal and the air and moisture locked in the pores of the paper may escape more easily from these sides. Further movement of the container through the paraffin bath is accompanied by rotation thereof so that the two remaining sides are in an approximately horizontal position facilitating the escape of the air and moisture. The movement of the container through the bath is such that the container is rolled within the bath to present the several sides of the container successively to the horizontal or at least causes them to assume substantial angles to the vertical. This is desirable inasmuch as the moisture content of the paper, as well as the minute quantities of air caught in the interstices of the fibers, are more readily dislodged from horizontally disposed paper surfaces than from vertically disposed paper surfaces. Thus particles of moisture and air expelled from the lower portion of a vertically disposed paper sheet will tend to re-attach themselves as they move upwardly or downwardly as the case may be, along the surfaces of the sheet. When the sheet is horizontally disposed, or disposed at a substantial angle to the vertical, any particles of moisture or air once discharged will rapidly separate themselves from the sheet by moving vertically upwardly or downwardly and will not have opportunity for such re-attachment. It is important therefore that the mechanism be of such character that the container as it passes through the bath causes each of the flat sides thereof, at one time or another, to be disposed either horizontally or at a substantial angle to the vertical.

It will be appreciated that, due to the fact that the container has parallel opposing side walls, when it is disposed in a truly horizontal position, air expelled from the upper surface of the lower side wall, and some air expelled from the vertical side walls may, upon rising, be intercepted by the upper horizontally disposed side wall and trapped against the lower surface thereof. Likewise water expelled from the upper side wall and vertical walls will descend and be intercepted by the lower horizontal side wall. Because of the further rolling motion imparted to the container however any such intercepted water or air is not permitted to remain upon or cover any spot upon which it is originally deposited, but will be caused to flow laterally so that at one time or another every portion of the entire area of each wall of the container is fully exposed to the bath.

My invention contemplates the provision of any suitable means for passing paper articles successively through a bath of paraffin and by means of which the positions of the articles are so changed during their progress through the paraffin that each of the several sides of each article are at one time or another disposed either horizontally or at an angle which so departs from the vertical, that the moisture and air particles may freely rise or fall therefrom depending upon the specific gravity thereof as compared with that of the bath.

The carriers which I employ for the purpose of immersing the containers are sufficiently large 5 interiorly to permit limited axial and transverse movements of any container housed therein during the coating operation. The containers will to a considerable extent oscillate within their respective housings in passing through the bath due to the surging of the paraffin bath itself, produced by the action of the carriers which are 10 successively entering the bath upon one side and machine. The loose retention of the containers within the carriers permits the paraffin to reach all surfaces of each container, both the interior 15 and the exterior surfaces, and the slight movements which each container may have within its carrier are sufficient to insure the complete and thorough coating of all the projecting fibers. It is highly important that these fibers be coated 20 as, in the absence of such protective coating upon a fiber, it will absorb moisture from the air or moisture with which it comes in direct contact and will transmit this moisture to the wall of the container, thereby softening the same 25 and decreasing its mechanical strength. It is, of course, of equal importance that the air and moisture between the interstices of the paper fiber of the container walls themselves be expelled and replaced by paraffin. Complete impregnation of the fibers themselves by paraffin is 30 not desired, but thorough continuous coating is essential.

With containers fabricated of paper such as have been described, it has been found that an 35 immersion of substantially ten seconds produces the desired effect upon the walls thereof, the air and moisture being expelled and the projecting filaments or fibers being completely coated while at the same time mechanical strength is 40 maintained. Longer immersion oftentimes results in production of containers of decreased strength due to impregnation of the fibers. When the paper is immersed for approximately ten seconds, as aforesaid, the temperature of the 45 paraffin is preferably maintained at approximately 165-175° F. It will be appreciated that with different weights and types of paper the time of immersion will vary and also that the temperature to which the paraffin has been heated 50 will have a bearing. In any case the object will be to immerse the paper for a sufficient time to insure that its moisture and air content is expelled, the projecting fibers thereof coated, and the interstices of the paper wall filled with paraffin. Continued immersion after these results have 55 been achieved is detrimental.

For the purpose of maintaining the paraffin at the desired temperature, suitable heating elements are incorporated within the housing 10. Such a heating element is indicated generally 60 at 100 and is seen to comprise a suitable tortuous conduit through which steam or other heated fluid may be passed. Gas heated or electrically heated elements may, of course, be substituted 65 for that shown. Also, and for the purpose of heating the upper portion of the mechanism enclosed within the housing, a second heating unit 101 is provided, this unit in the present instance also comprising a tortuous conduit for the circulation of steam. All parts of the conveyor, 70 all of the carriers, and in fact all parts enclosed within the housing are maintained at all times at a temperature above that of the melting point of paraffin so that any paraffin which is carried 75 upwardly out of the bath upon the conveyors will

remain liquid and fall again to the bath without congealing and thereby clogging the machine.

The time of immersion of the containers may be varied in various ways, as by regulating, for instance, the speed of the conveyor. Inasmuch 5 as the coating unit may comprise a portion of a complete automatic machine, however, it is not desirable to vary its operating speed and hence the time of immersion of the containers may be conveniently regulated by varying the depth of 10 the paraffin bath, lowering the level of the upper surface of the bath resulting in a decreased time of immersion, and raising of the level of the upper surface resulting in an increased time of im- 15

As each container emerges from the paraffin bath it is disposed with its closed bottom end uppermost, permitting the coating to flow out of the interior of the container and off of its outside surfaces. The lowermost surface of the container rests on a convex surface of the carrier 20 so that there is a comparatively small area of contact of the container with the carrier, permitting the paraffin to have maximum opportunity to escape between the lower wall of the container and the convex inner surface of the then 25 bottom supporting wall of the carrier. The duration of the draining of the containers may be approximately eighteen seconds, but at any rate sufficiently long to permit the flowing off of all 30 free flowing paraffin.

When a freshly immersed container reaches the discharge position, in which position the carrier in which it is housed occupies the position indicated at D in Figure 1, its walls are substantially free of excess paraffin, the draining operation being substantially completed. A slight further drainage occurs, however, after ejection of the container from the carrier and during inversion of the container by the mechanism previously described and which is illustrated in Figure 6. Thus, after the container has been again positioned vertically with closed end lowermost, as indicated at C⁴ in Figure 6, there is a slight downward drainage along the vertical walls and this 45 paraffin when later solidified, stiffens, reinforces and renders entirely leakproof the bottom section 50 of the container, where the pressure of any liquid later introduced is naturally the greatest.

Having thus described the invention, what is 55 claimed as new and desired to be secured by Letters Patent is:

1. The method of coating the inside and outside surfaces of an empty paper container having a closed end and an open end, a flat bottom and flat side walls, which comprises introducing the container bottom end foremost into a bath of molten paraffin, moving the same, while immersed, in such manner that all wall surfaces thereof are successively disposed at angles to the vertical, and removing the same from the bath 60 bottom end foremost.

2. The method of coating the inside and outside surfaces of an empty paper container having a flat closed bottom and an open top and flat side walls, which comprises introducing the container bottom end foremost into a bath of molten paraffin while the longitudinal axis of the container is maintained at an angle to the vertical, moving the container, while immersed in such 65 manner that all wall surfaces thereof are successively disposed at angles to the vertical, and removing the same from the bath bottom end foremost.

3. The method set forth in claim 2 in which

the container is loosely held during immersion to permit limited movements in all directions under the influence of currents of the molten paraffin.

- 5 4. The method of coating the inner and outer surfaces of an empty paper container the walls of which are flat, which comprises, moving the

container, while immersed in a bath of molten coating material so as to dispose each wall surface thereof at an angle which so departs from the vertical that air and moisture may freely rise or fall therefrom.

HENRY T. SCOTT.
